Patented Mar. 26, 1918.

UNITED STATES PATENT OFFICE.

ASHTON G. STEVENSON, OF NEW YORK, N. Y., ASSIGNOR TO WILLIAM H. CROSS, OF MENOMONIE, WISCONSIN.

TYPE FURNITURE AND TYPE-FURNITURE MOLD.

1,260,828.

Specification of Letters Patent. Patented Mar. 26, 1918.

Application filed August 21, 1917. Serial No. 187,349.

To all whom it may concern:

Be it known that I, ASHTON G. STEVENSON, a citizen of the United States of America, residing at New York city, State and county of New York, have invented a new and useful Type Furniture and Type-Furniture Mold, of which the following is a specification.

This invention has reference to certain new and improved means and methods of casting type furniture so-called on intertype, linotype and similar machines. The apparatus is designed to cast type furniture from two ems pica upward.

My invention aims at producing a uniformly satisfactory product, the furniture when finished being comparatively light yet strong and durable. To that end I produce a mold the core of which is properly constructed and reinforced so that it will not warp, bend or break during the casting operation. The means and method which I have designed and employ in the practising of the method is more fully described in the accompanying application and is illustrated in the accompanying drawings, in which:

Figure 1 is a perspective view of a mold with the closure or front piece removed.

Fig. 2 is a relatively enlarged front elevation of the same parts with the portion of the front in place.

Fig. 3 is a cross section on the line 3—3.

Fig. 4 is a plan view of a detail broken away.

Fig. 5 is a perspective view of another detail broken away.

Fig. 6 is a horizontal section of a part of a piece of type furniture.

Fig. 7 is an edge elevation of the same piece viewed from above.

Fig. 8 is a view similar to Fig. 4 showing a modification.

It will be understood that I have shown my new apparatus only in its preferred form and that it is capable of a wide variety of modifications without departing from the spirit or scope of the invention. The mold comprises the usual body 10 which is adapted to be secured to or mounted upon the ordinary wheel or disk in the usual manner. 11 is a cap or cover mounted in any suitable way on the body 10. In the space within the mold body 10 where the slug is to be cast, is located a core 12, the upper and lower sides of the core being spaced apart

from the corresponding walls of the mold body so as to form at the rear an upper and a lower slot through one of which the molten metal under pressure is introduced when a piece of furniture is to be cast. The core 60 is preferably tapered or beveled transversely, and at its forward or narrower edge I form slots or notches extending toward the rear edge of the core, the sides of the slots flaring outwardly. Thus, when molten metal is introduced that part of the molten metal standing in the said notches will form transverse supporting bridges between the two opposite sides of the furniture. In general, the parts I have thus far described are well 70 known but are not practical of employment in producing a piece of furniture of greater length than about 13 ems pica, because the pressure of the molten metal at the rear edge of the core will buckle and distort the 75 same producing imperfect and unsatisfactory work. To prevent this, and to permit of forming a piece of furniture of any desired length, I provide suitable means to effectively prevent the aforesaid buckling of 80 the core. 14 represents a removable front piece or closure for the mold which piece is carried by a matrix 15 preferably in the form of a block which may be supported by the matrix carrier in the usual manner. 85 This closure piece 14 is provided with a face piece 16 which extends into the mold body to form a front core, the side walls of said face 16 being substantially beveled to permit the metal to flow into the space around said 90 piece and between the same and the walls of the mold body, whereby said face piece will act as a core. At the front edge of the core 12 between the notches therein I provide pins or other suitable projections 18—18 95 which when the mold is assembled in place ready for use engage the flat or supporting surface of the piece 16 which latter then constitutes a reinforcing abutment for the core 12 in addition to its aforesaid function, 100 hence, when the pressure of the molten metal is applied to the rear edge of the core 12 it cannot possibly buckle, bend or distort the same by reason of the weaknesses therein produced by the notches, and hence, the 105 slugs or furniture produced will be uniformly accurate. The cores 12 and 16 serve to displace sufficient metal to make the furniture comparatively light without sacrifice to strength because of the reinforcing or 110

bridging bars 19-19 which unite the opposite sides of the same.

Instead of forming relatively small pin-like projections 18-18 along the notched edge of the core 12, I may actually make those portions of the core between the notches of sufficient length to actually engage the face piece 16 when the parts are assembled so as to get a direct reinforcement, instead of an indirect reinforcement through the medium of the pins 18. In some instances this modification, which is illustrated in Fig. 8, is preferable. It is obvious that the core pieces 12 and 16 may be made of various shapes and sizes so that different ones can be substituted. In this instance, the piece which carries the core piece or projecting portion 16 is detachably connected to the matrix or quad block by a dovetail joint that permits the ready substitution of other face pieces.

A piece of furniture constructed by my improved mold possesses the further advantage of permitting gasolene or other cleaning agent employed to drain through the passages between the bridges 19-19, said passages being formed during the making of the furniture as a result of causing the notched edge of the core 12 to bear against the face 16 during the molding operation. As a result, my invention resides not alone in the means and method of casting the furniture, but also in the furniture itself.

I claim:

- 35 1. In a mold of the character described, a mold body having a passage therethrough, closure means for the front end of said passage and a core for partially closing the rear end of said passage, the forward edge 40 of said core being notched, those parts of the core between certain notches being supported by said closure.
- 45 2. In a mold of the character described, a mold body having a passage therethrough, closure means for the front end of said passage and a core for partially closing the rear end of said passage, the forward edge

of said core being notched, those parts of the core between certain notches being supported by said closure, said means comprising projections at the inner edge of said core. 50

3. In a mold of the character described, a mold body having a passage therethrough, closure means for the front end of said passage and a core for partially closing the rear end of said passage, the forward edge of said core being notched, those parts of the core between certain notches being supported by said closure, the closure means 55 60 for the front end of said mold projecting partially into the space in the mold body to act as a core.

4. In a mold of the character described, a mold body having a passage therethrough, 65 a closure for the front end of said passage, a core held within the rear end of the passage and partially closing the same, and the forward end of said core contacting with the front closure at longitudinally spaced 70 points.

5. In a mold of the character described, a mold body having a passage extending therethrough from front to rear, a removable closure for the forward end of the passage, and a fixed core within the rear end of the passage partially closing the same, the forward end of the core contacting with the front closure at predetermined points 75 80 for support thereby.

6. In a mold of the character described, a mold body having a passage extending therethrough from front to rear, a closure for the front end of the passage having a central longitudinal core-like projection extending within the forward end of the passage, a core held within the rear end of the passage and providing a similar opposed central longitudinal member, the inner ends of said member and projection being separated 85 90 and the opposed faces thereof being formed for contact with each other on reduced areas.

ASHTON G. STEVENSON.
